REIN-PULL RECORDER

Francis Du Pont Ammen, Los Angeles, Calif.

Application March 8, 1941, Serial No. 382,351

10 Claims. (Cl. 265—2)

This invention relates to a device to be employed in connection with horse racing.

It is a well known fact that sometimes a jockey during a race, will hold his horse in the stretch, to prevent his horse from winning. In fact, this is a common practice and is done sometimes with the knowledge, and under the instructions of the owner or trainer of the horse. This practice is, of course, dishonest if betting is taking place, and is a source of losses and annoyance to the spectators who may be betting on the horse. If the judges see evidence of such holding, the jockey may be ruled off the track, or reprimanded. When the animals are charging in the stretch, many of the jockeys and their horses are concealed by the other horses. Hence it is extremely difficult to detect this practice of holding a horse in the finishing stretch.

Holding back a horse in the early portion of a race is perfectly permissible, and many a horse should be ridden in that way in order to save his energy for the sprint at the finish.

The object of this invention is to provide a simple and reliable device for indicating whether a horse has been pulled wrongfully in a race; in other words, it charts a record of the pull on the rein of a racing horse from the start to the finish, the general purpose being to show for the benefit of the judges after the race, and for the benefit of the betting public, whether each horse in the race has been honestly ridden to win.

This device is also useful, to enable the manner in which a horse is ridden by the jockey in practice runs, to be graphically indicated to the owner or trainer, the record card produced on the device operating, for example, to indicate at what point on the track the horse was held back, with the hope of attaining by different trials, the shortest time for a certain length of race for which the horse is being trained.

One of the objects of the invention is to provide a device that is capable of being associated with the bit of the bridle and connected to the rein, and so constructed that the galloping of the horse will automatically drive a record card, while a recording member such as a pencil, traces a line on the card that indicates at all times, the tension in the reins, and operating so that when the horse is not galloping, the record card is not driven.

In its preferred embodiment, the invention employs an oscillator or pendulum mounted to swing in the plane in which the horse is running ahead. This oscillator arm is nearly in balance,

and mounted so that at each spring of the horse the arm will move, and its motion will be imparted to a platen carrying the card.

In racing, the motion of the horse's head is intermittently forward at varying speed, and also up and down. A further object of the invention is to provide means for regulating the level of the path of swing of the oscillator arm with respect to the axis on which it rocks, therefore enabling more or less of the intermittent forward motion or up-and-down motion of the bit to be utilized in controlling the inertia forces that energize the oscillator.

Further objects of the invention will appear hereinafter.

The invention consists in the novel parts and combination of parts to be described hereinafter, all of which contribute to produce an efficient rein-pull recorder.

A preferred embodiment of the invention is described in the following specification, while the broad scope of the invention is pointed out in the appended claims.

In the drawing:

Fig. 1 is a side elevation of the head of a racing horse, and illustrating a bridle provided with a recording device embodying this invention.

Fig. 2 is a side elevation of this recording device upon a larger scale, and indicating adjacent portions of the bridle broken away.

Fig. 3 is a longitudinal section taken in the line 3—3 of Fig. 2. Certain parts are broken away.

Fig. 4 is a fragmentary vertical section taken about on the line 4—4 of Fig. 3 upon a still larger scale, and particularly illustrating details of means that is preferably employed for enabling the level of the path or field of oscillation of the oscillator arm to be regulated with respect to its axis of oscillation.

Fig. 5 is a diagrammatic view illustrating a record card, and showing a graph such as would be traced on the card if the racing horse was not pulled at any time during the race, but only to stop the horse after the finish.

Fig. 6 is a view similar to Fig. 5, but showing the graph of a race in which the horse was held back slightly, in the first portion of the race, and badly pulled in the stretch.

In practicing the invention, a recording device is provided that indicates the amount of pull on the rein on a moving recording member or card, the said recording member being moved proportionally with the progress of the race.

Any suitable driving means may be provided for the platen that carries the recording element,

such as a small paper or card, but this is preferably accomplished by means of an inertia-controlled oscillator member, so constructed that it will oscillate only when the animal is galloping. The advantage of this is that the cards can be put on their platens before the horses parade before the grandstand.

In the preferred embodiment illustrated in the drawing, the end of the bit B is provided with a guide head 1 for carrying a tension device including a shoe or slide 2, the rear end of which is connected to the rein 3, and the pull in the rein is resisted by a coil spring 4 on the projecting forward end of the slide, that thrusts between the head 5 and the forward end of the guide head.

The head 1 carries recording means, preferably including a rotary platen 6 of disc-form, mounted to rotate on a horizontal pin or stud 7 projecting out from the side of the guide head 2.

Preferably located between the platen and the guide 1 is an oscillator element in the form of an arm 8. This arm is a floating part, that is to say, it is mounted to swing in the front-and-rear plane in which the animal is advancing, so that the inertia of the arm will cause it to oscillate to and fro while the animal is racing. The motion of the oscillator is imparted to the platen to drive it in a forward direction around its axis of rotation on the pin 7. For this purpose I may provide the arm 8 with a spring-pressed driving pawl 9, engaging teeth 10 formed continuously along the periphery of the platen. A spring-pressed detent pawl 11, or other suitable means may be provided for holding the platen against backward rotation.

The device is provided with means for regulating the position of the arm 8 so as to adapt it to the peculiarities of motion of the horse in running, that is to say, locate the arm in an optimum angle for utilizing the inertia forces developed in the arm as the horse leaps forward and lands in his stride.

For this purpose I provide an adjustable bracket 12 of arcuate form adjustably seated in an arcuate socket 13 in the outer face of the guide-head 1. The adjustment is effected by providing a curved slot 14 with a stud in the slot provided with a clamping nut 15.

An adjustable return spring 16 seating against the lower end of the bracket, returns the arm after it has swung forward or down, forcing the arm up or back against an adjustable stop-screw 17 carried by the upper end of the bracket 12. An adjusting screw 18 carried in a toe of the arm 8, adjusts the coil spring 16 which is a compression spring. This adjusts the angle of the arm 8 with respect to a horizontal line through the pin 7. In other words, the location of the path of swing of the oscillator, can be adjusted so that the oscillator will swing more or less up and down, or more or less forward and back in the front and rear plane. This is advantageous because it enables the arm 8 to be held in a location at which the maximum amount of energy can be attained from the inertia forces developed by the motion of the horse's head, in galloping. The arm 8 and bracket 12 constitute an assembly adjustable as an assembly around the axis of the pin 7.

A recording stylus or pencil 19 is provided preferably mounted on the end of a bow spring 20 carried by the slide. The spring 20 presses the point of the hard pencil against a record element or card 21 secured to the face of the platen. The card is provided with spaced circular scale lines 22 (see Figs. 5 and 6) numbered progressively as a scale for indicating force, from

the center radially outward. The card is also formed with a central opening 23 to fit over a follower-screw 24 that holds the platen on the pin or stud 7. One or more spring clips 25 are provided on the platen, with small spurs 26 on their inner sides to clamp and impale the card, and thereby insure its rotation with the platen.

If the race is run without holding the horse at any point on the course, the pencil will rule 10 a line having the characteristics of the line 27 in Fig. 5, which is nearly circular in form. This line originates at the point 28 where the race starts. The portion 31 of the line indicates the 15 pulling of the horse to stop him after he has crossed the wire on a mile track, for example.

Fig. 6 illustrates the character of graph or line 30 traced in riding a horse that was held somewhat at the point 31, and held again badly at the point 32 in the stretch just before the finish. The guide-head is provided with a supporting extension 33 attached to the side straps 34 of the bridle. This part may carry the detent pawl 11.

Wherever possible, the parts of this device should be composed of aluminum or some light alloys. But the oscillator arm, if necessary, may be made of a metal having greater specific gravity and, if desired, may be weighted on its outer end so that its center of gravity is well out from its axis of swing.

The spring 16, the oscillator arm 8, and the stop 17, should be designed and adjusted so that the oscillator will swing about in time with the rhythm or frequency of the horse's leaps when 25 in his racing gallop.

For the sake of lightness, the slide 2 may be made of hollow form. It is provided with a cotter pin 2a operating as a stop.

If desired, a leather guard 35 may be provided 40 between the guide head 1 and the side of the horse's mouth.

Many other embodiments of the invention may be resorted to without departing from the spirit of the invention.

What I claim is:

1. In an indicator for recording the pull on a rein of a racing animal, the combination of a slide connected to the rein, a spring distorted by movement of the slide, means for guiding the slide, a recording pencil connected to the slide to move therewith, a movable platen to carry a card to cooperate with the pencil, an inertia-controlled oscillator actuated by each leap of the animal, and means associated therewith for driving the platen proportionally to the distance traversed by the animal in the race, to enable the pencil to record a continuous line on the card.

2. In an indicator for recording the pull on a rein of a racing animal, the combination of a slide connected to the rein, a spring distorted by movement of the slide, means for guiding the slide, a recording pencil connected to the slide to move therewith, a rotary platen to carry a card to cooperate with the pencil, an inertia-controlled oscillator arm mounted to rock about the axis of the platen and actuated by the leaps of the racing animal, and means associated with the oscillator arm and the platen for imparting movement to the platen from the oscillator arm.

3. In an indicator for recording the pull of a rein of a racing animal, the combination of a slide connected with the rein, means for guiding the same, a recording pencil connected with the

slide, a spring for resisting the pull on the rein, a rotary disc-form platen for carrying a recording card to cooperate with the pencil, an inertia-controlled oscillator arm mounted to rock on the axis of rotation of the platen, actuated by the leaps of the racing animal, said platen having teeth and said oscillator arm having a driving pawl for engaging the teeth to rotate the platen as the animal races forward.

4. In an indicator for recording the pull of a rein of a racing animal, the combination of a slide connected with the rein, means for guiding the same, a recording pencil connected with the slide, a spring for resisting the pull on the rein, a rotary disc-form platen for carrying a recording card to cooperate with the pencil, an inertia-controlled oscillator arm mounted to rock on the axis of rotation of the platen, actuated by the leaps of the racing animal, said platen having teeth and said oscillator arm having a driving pawl for engaging the teeth to rotate the platen as the animal races forward, and a detent pawl for preventing rotation of the platen in a backward direction.

5. In an indicator for recording the pull on the rein of a racing animal, the combination of a slide connected to the rein, a spring for resisting the movement of the slide, a rotary platen for carrying a card, an inertia-actuated oscillator arm mounted to swing substantially in the front and rear plane in which the animal is advancing, and oscillated by the leaps of the racing animal, means for regulating the level of the path of swing of the arm with respect to the axis on which it swings, means for imparting the movements of the arm to the platen, and means controlled by the slide for tracing a record line on the card.

6. In an indicator for recording the pull on the rein of a racing animal, the combination of recording means connected to the rein, including a pencil and a platen for carrying a recording card; an inertia-controlled driving device for driving the platen and the recording card proportionally to the advance of the racing animal, said driving device including an oscillator arm mounted to rock in a front-and-rear plane on an axis, oscillated by the leaps of the racing animal and means for regulating the angle of the arm with respect to a horizontal line passing through the said axis.

7. In an indicator for recording the pull on the rein of a racing animal, the combination of a slide connected to the rein, a spring for resisting the movement of the slide, a rotary platen for carrying a card, an inertia-actuated oscillator arm mounted to swing substantially in the front-and-rear plane in which the animal is advancing, a relatively fixed means mounted for adjustment substantially about the said axis, means for imparting the movements of the oscillator arm to the platen, a spring between the oscillator arm and the relatively fixed means, and means controlled by the slide for tracing a recording line on the card.
- 10 8. In an indicator for recording the pull on a rein of a racing animal, the combination of a slide connected to the rein, a spring distorted by movement of the slide, means for guiding the slide, a recording pencil connected to the slide to move therewith, a movable platen to carry a card to cooperate with the pencil, and a floating part independent of the pull on the rein actuated through the agency of the motion of the racing animal for driving the platen proportionally with the distance traversed by the animal during the race, to trace a record line on the card.
- 15 9. In an indicator for recording the pull on the rein of a racing animal, the combination of recording means connected to the rein, including a marking element and an element for carrying a recording card; and an inertia-controlled driving device actuated by the leaps of the racing animal for driving one of said elements proportionally to the advance of the racing animal.
- 20 10. In a device for continuously recording the relative rein pulls in the bridle of a racing animal as it progresses along a race course, the combination of a member for supporting a moving recording element and a marking means thereon, mechanical means associated with the recording element capable of exerting a force independent of that of the pull in the rein, to effect continuous progressive movement of the recording element proportional to the advance of the animal along the race course, and means for moving the marking means across the recording element proportionally to the pulling forces in the rein, thereby continuously producing a force-recording line on the recording element
- 25 as the animal runs along the course.
- 30
- 35
- 40
- 45
- 50
